MATTHEW BURDA, OF CHICAGO, ILLINOIS.

TRUNK-LOCK.

1,217,146.

Specification of Letters Patent. Patented Feb. 27, 1917.

Application filed May 31, 1916. Serial No. 100,778.

To all whom it may concern:

Be it known that I, MATTHEW BURDA, a subject of the Emperor of Austria-Hungary, residing at Chicago, in the county of Cook 5 and State of Illinois, have invented certain new and useful Improvements in Trunk-Locks, of which the following is a specification.

The essential object of this invention is to 10 provide a trunk lock of the multiple-bolt type in which there are two bolts adapted to pass through or coöperate with a suitable staple or latch. Both bolts are adapted to be operated by the same key, and each bolt must 15 be suitably actuated in order to lock or unlock the device.

In the drawings forming part of this specification and in which like numbers of reference denote like parts wherever they 20 occur, Figure 1 is a front elevation of a lock constructed in accordance with the invention, the removable section or cover of the casing being clamped or bolted in place; Fig. 2 is a view of the parts as they appear 25 when the casing cover is removed; Fig. 3 is a view similar to Fig. 2, the outer one of the two pivoted tumblers which control the bolt-carrying sliding plate likewise being removed; Fig. 4 is a view similar to Figs. 2 30 and 3 in which the bolt-carrying sliding plate is exposed; Fig. 5 is a view showing the rocking bolt, the bolt-carrying sliding plate depicted in Fig. 4 being removed; Fig. 6 is a vertical sectional view of the line 6—6, 35 Fig. 5; Figs. 7 and 8 are views, respectively, of the outer and inner tumblers by which the bolt-carrying sliding plate is locked in place; Fig. 9 is a view of the bolt-carrying 40 sliding plate showing the side opposite the one exposed in Fig. 4; Fig. 10 is a perspective view of the staple-holding strap and the staples attached thereto; Fig. 11 is a detail in section on the line 11—11, Fig. 5; Fig. 12 is a detail in section on the line 12—12, Fig. 45 5; Fig. 13 is a detail in section on the line 6—6, Fig. 5; and Fig. 14 is a detail in section on the line 14—14, Fig. 11.

The specific embodiment of the invention depicted in the drawings is that of a lock 50 best adapted to be used upon a trunk or chest, in which the outer casing 1 within which all of the movable parts are contained, is mortised into the base or bottom part of the trunk. The strap 2 can be secured by 55 screws 3 to the lid or cover of the trunk, and the staples 4, which are formed integrally

with or otherwise permanently secured to the strap 2, project outwardly and normally downwardly from the cover or lid, and are arranged in registration with suitable slots 60 5 in the top member 6 of the outer casing 1. The base-plate of the casing 1 bears posts 7 which are provided with a squared-off head from which the screw-threaded end 8 projects, and the removable cover-plate 9, which 65 both conceals and protects the operating parts, is adapted to be screwed or secured in place by nuts 10, resting against the heads 8 of posts 7.

Projecting outwardly from the base-plate 70 of the casing 1 is the key post 11, and the key 12 provided with the hollow end 13 is adapted to fit over and revolve around said key post 11 as an axis. A tube 14 slotted at 15 is secured to the cover-plate 9, and the 75 axis of said tube 14 coincides with the axis of the key post 11 and of the stem of the key 12. Said tube 14 is revolubly mounted upon the plate 9 and is permitted to move in a counter-clock-wise direction 1 through only 80 a few degrees of arc and then back again to a normal position. The arm 16 is secured to said tube 14 and extends radially therefrom, said arm being outside of the plate 9, but being placed closely to or in engagement 85 with said plate. Upon the outside of plate 9 there is fastened a spring-like member 17 which is depicted in the drawings as having an ornamental shape, but which may be made of any desired shape. Said member 17 90 is fastened to the plate 9 by rivets or bolts 18 at its right end but at its left end (Fig. 1), said member 17 is permitted to move toward or away from the plate 9. The inner side of the member 17, meaning the side 95 which is adjacent to the plate 9 (Fig. 13) is hollowed out at 19 to receive the arms 16, said hollowed part 19 being provided with a beveled edge, so that when the arm 16 is swung in a counter-clock-wise direction 100 (Fig. 1), said arm 16 will ride upon said beveled edge and will lift or force the member 17 outwardly or from the plate 9 for a short distance. The right hand end of said member 17 cannot move on account of the 105 bolts 18, but since the member 17 is made of spring metal or similar material it will return to normal position in close engagement with cover-plate 9 whenever the arm 16 is placed as indicated by the dotted lines in 110 Fig. 1. The plate 9 is provided with the keyhole 20, which is in alinement with the

slot 15 in the tube 14, and the eye 21 of said keyhole serves not only to permit passage of the pin 12 of the key thereto, but also permits the tube 14 to be secured to the plate 9. 5 The key depicted in the drawings is provided with the bit 22 in which the slot or gating 23 is cut, and said bit 22 is adapted to pass through the keyhole 20 in the plate 9 as well as through the slot 15 in the tube 14.

10 The slideable bolt-carrying plate 24, shown best in Figs. 4 and 9, comprises a flat plate of metal provided with suitable perforations, the use and function of which is hereinafter set forth, and bearing, also, certain operative parts thereupon. At its upper edge said plate 24 carries the bolt-members 25, which are preferably three in number, separated by the spaces 26, and beneath said bolt members 25 are recesses 27 formed by cutting away part of the metal of the sliding plate 24. When the staples 4 are allowed to enter the spaces 26 the sliding plate 24 can be moved toward either the right or left (Figs. 2 and 3), and under such circumstances the device will be locked because the staples 4 will be held in place by the bolts 25, which bolts 25 are connected with the main body of the sliding plate 24 by the webs 28. Since the strap 2 to which the staples 4 are fastened is permanently secured by screws 3 to the lid or cover 29, it is obvious that the staples are devoid of longitudinal movement and can be moved only toward or away from the casing 1 as the cover 29 is lowered or raised. The casing 1 being mortised in the main body of the trunk or other article upon which the lock is used is secured permanently in place, and the staples 4 are held by the bolts 25 when the parts are in the positions depicted by way of example in Figs. 2, 3, and 4. When, however, the sliding plate 24 and the bolts 25 are moved to a point where the spaces 26 are in registration with the slots 5 in the top 6 of the casing, the staples 4 may then be permitted to pass through the spaces 26, and when the slots 5 and spaces 26 are in registration, but at no other time, the lid may be raised.

50 Secured to the base-plate 1 is a shank 30 (Fig. 4) the head of which projects through the slot 31 in the sliding plate 24. The head of this shank 30 is rounded off and the tumblers 32 and 33 are pivotally mounted upon said shank 30. To each of said tumblers 32 and 33 a spring 34 is fastened and said tumblers 32 and 33 are recessed or slotted at 35 and 36. A stud or projection 37 (Figs. 2 and 4) is carried upon the sliding plate 24, which stud is received within the slots 35 and which must pass through the slots 36. Unless the proper key is used, the tumblers 32 and 33 will not be moved the right distance to permit the stud 37 to enter and pass 65 through the longitudinal slots 36, and the

bit 22 of the key 12 must be of the right height and the slot or gating 23 must be cut at the right position and of the right depth; otherwise when the key is revolved it will not act properly upon the tumblers 32 and 33 and will not move said tumblers to the exact positions which they must respectively attain in order to permit the stud 37 to ride into and through the slots 36, and, obviously, unless the stud 37 can enter the slot 36 the sliding plate 24, together with the bolts 25 which are carried thereupon, must remain immovable. The sliding plate 24 carries a strap 38 recessed or slotted at 39, which member 38 receives the loose ends of the springs 34. The tumblers 32 and 33 are rocked upon the pin 30 as a pivot and moved in a counter-clock-wise direction by the action of the key 12, but are returned to normal or starting position because of the resilience of the springs 34. The member 38 is of a sufficient length to permit it to engage the springs 34 regardless of the position of the sliding plate 24.

Although the parts thus far described suffice to constitute an ordinary lock which is, obviously, a lock so constructed as to be readily manipulated and picked, it is because of the combination of the parts previously described with those hereinafter to be described that the more valuable and salient features of the invention arise. The pin or shaft 40 (Fig. 5) is rigidly secured to the base of the casing 1, and the trigger 41 is pivotally mounted upon said pivot 40. When said trigger 41 is in the position depicted in the full lines of Fig. 5 the bolt 42 carried upon or integral with the trigger 41, will project beneath and across one of the spaces 5 through which a staple 4 must pass whenever the lid 29 is to be locked or unlocked, and when the bolt 42 is in that position the staple 4 can neither enter or leave the space 5; hence, although the bolts 25, by their coöperation with the staple 4, serve to lock the staples 4 in place or permit them to be moved as the case may be, the trigger 41 and the bolt 42 thereupon serve the same purpose, and it is necessary to actuate both the trigger 41 and the sliding plate 24 and to actuate both of said members in the proper manner and at the proper time in order to permit the staples 4 to be unlocked. The trigger 41 is recessed at 43 beneath the bolt 42, and in said recessed or cutaway portion 43 the staple 4 is adapted to be received when the trigger is in the full line position of Fig. 5. A spring 44 is secured to the trigger 41 and one end of said spring 44 normally engages the stud 45, the normal action of said spring 44 being to move the trigger from the full line to the dotted line position whenever the trigger 41 is released. In the trigger 41 is a recess or slot 46 (Fig. 11) which receives the stud or 130

projection 47 carried near one end of the spring-controlled rocking catch 48. The catch 48 is pivotally mounted upon a shaft 49 which passes through a bifurcated stud 50 formed upon the base of the casing 1, and the catch 48, therefore, is permitted to have a slight rocking movement traveling in a plane at right angles to the plane in which the trigger 41 is adapted to rotate. When 10 the parts are in the full line position of Fig. 5, the stud 47 will seat in the notch or recess 46 and will hold the trigger 41 in said full line position, but when, however, the left hand end (Fig. 11) of the catch 48 is moved away from the base member 1 said stud 47 is lifted out of the notch 46, and thus 15 the trigger 41 is snapped by the spring 44 from the full line to the dotted line position of Fig. 5. At a point adjacent to the key 20 post 11 the metal of the casing 1 is removed at 51 and the beveled end 52 of the catch 48 is seated in said recess 51 (Fig. 14). When 25 the edge 53 of the key-bit 22 rides over said beveled end 52, and when it is pressed thereupon, the beveled end 52 of the pivoted catch 48 is pressed toward the casing 1, thereby 30 moving the opposite end away from the casing and carrying the stud 47 out of the recess 46, thus releasing the trigger so that it may be actuated by the spring 44.

The trigger 41 bears the shoulder 54, and upon the sliding plate 24 is a stud 55 (Fig. 9). When the sliding plate 24 is pushed toward the right in Fig. 9 or to the left in 35 Figs. 2 and 3, the stud 55 will engage the shoulder 54, and will ride therealong, and as it does so, will actuate the trigger 41 and cause same to rotate upon its axis until it reaches the full line position of Fig. 5. 40 When the trigger does reach that position, the stud 47 carried upon the pivoted catch 48 will seat in the notch 46 (Fig. 11) and lock the trigger in place, and spring 56 interposed between the pivoted catch 48 and 45 the casing normally tends to keep the stud 48 seated in the notch 46, but when the edge 53 of the key-bit 22 rides over the beveled end 52 of the pivoted catch 48, the catch thereby is caused to rock upon its pivot 49 50 against the resistance of the spring 56.

The stud 55 is upon that side of the sliding plate 24 which is exposed in Fig. 9, and upon the same side is a pivot 57 around or upon which plate 58 is adapted to rotate. 55 Said pivoted plate 58 is perforated at 59 and is normally kept in the position indicated in the full lines (Fig. 9) by the spring 60, the free end of which bears against the stud 61, and when the pivoted plate 58 is moved as 60 hereinafter described to the dotted line position the perforation 59 in the plate 58 is adapted to register with the slot 62 formed in the sliding plate 24. At its lower edge (Figs. 4 and 9), the sliding plate 24 is provided with a recess 63 having the curved

edges 64 against which the key-bit 22 is adapted to impinge, and when the key is rotated upon the key post 11 as an axis, the key causes the plate 24 to slide in one direction or the other according to the direction of rotation of the key, because the key-bit 22 strikes the edges 64 of the recess 63. The sliding plate 24 is provided with another recess 65, one edge 66 of which is formed of the metal of the sliding plate 24. The edge 67, which is at the left hand end of Fig. 4 and at the right hand end of Fig. 9 is also adapted to be engaged by the key-bit 22, but if the plate 58 be lifted to and retained in the dotted line position of Fig. 9, the edge 67 will be lifted out of the way of the key-bit 22 and the key will rotate idly in the space 65 without actuating the sliding plate 24. The member 17 carries the pin or stud 68 which projects inwardly through the outer cover 9 and through the slot 62 in the bolt-carrying plate 24. If the pivoted plate 58 be moved to the dotted line position of Fig. 9 at a time when the perforation 62 of said plate 58 is in registration with the stud 68, said stud will seat in the perforation 59 and will retain the pivoted plate 58 in the dotted line position. When, however, the tube 14 is rotated in a counter-clock-wise direction (Fig. 1) the arm 16 causes the left 95 hand end of the spring metal plate 17 to be moved away from casing member 9; and as the member 17 thus moves, the stud 68 rides out of the perforation 59 and the pivoted plate 58 is snapped back by means of spring 100 60 to full line position (Fig. 9).

The operation of the parts is as follows:

Assuming that at the locked position the sliding plate 24 is at the extreme left of the casing 1, as indicated in Fig. 4, that the trigger 41 is in the full line position (Fig. 5), and that the pivoted plate 58 is in the full line position (Fig. 9), the operator inserts the key and rotates same in a clockwise direction, whereupon the bit 22 raises the pivoted tumblers 32 and 33 each to the point where the lug 37 enters the left-hand slots 36, thus permitting the sliding plate 24 to travel toward the right, the movement of said plate being caused by the pressure of 110 the bit 22 upon the curved edge 67 of the pivoted plate 58. The first revolution of the key will move the sliding plate 24 for about half its full length of travel or until the projection 37 seats in the middle recesses 35, 115 120 The operator continues the revolution of the key giving it a second complete revolution, by means of which second revolution the sliding plate 24 will be carried to the dotted line position of Fig. 2, in which position the 125 sliding plate 24 is at the extreme right of the casing. When the key makes said second revolution, it forces the plate toward the right because of the engagement of the bit 22 upon the left edge 64 (Fig. 9) or right 130

edge 64 (Fig. 4) of the recess 63. It is obvious that as the sliding plate 24 moves from the full line position of Fig. 2 to the dotted line position in the same figure, the recesses 26 which separate the bolts 25 from each other come into registration with the recesses or slots 5 in the upper edge of the casing 1, but although in such position the bolts 25 do not prevent withdrawal of the staples 4, the lid 29 cannot be lifted because the bolt 42 on the pivoted trigger 41 still serves to retain the staples 4 in locked position indicated in Figs. 1 and 5 of the drawings. In order to release the trigger 41, it is necessary to 15 continue the rotation of the key until the bit 22 reaches the angle shown in Figs. 2 and 3, same being about the position as the 9 on the ordinary clock dial, and when the key is thus moved, it must be pushed toward the 20 base of the casing 1 and away from the cover-plate 9; that is to say, the key would have to be pushed downwardly in Figs. 6 and 12 so that the edge 53 of the bit 22 will press upon and move the beveled end of the 25 nose 52 of the pivoted catch 48. As the edge 53 thus engages the pivoted catch 48, it depresses one end of said catch while elevating the other, thus lifting the stud 47 out of the notch 46, whereupon the spring 44 snaps the 30 pivoted trigger 41 to the dotted line position of Fig. 5, in which position the bolt 42 is out of the path of travel of the staple 4 and, so far as the trigger 41 is concerned, the lid 29 may be raised. The operator thereupon 35 must turn the key in a counter clock-wise direction and move it through about 280° of arc until the key stands at about the position of the 12 on a clock dial, and in thus moving in the counter-clock-wise direction, 40 the bit 22 again enters the recess 63, engages the right-hand edge 64 (Fig. 9), thus causing the sliding plate 24 to move a short distance toward the left (Figs. 2 and 3), until the recesses 26 are in registration with the 45 staples 4.

When it is desired to lock the device, the lid 29 is lowered and the staples 4 resume the position indicated in Figs. 1 and 5, and the key is rotated in a counter-clock-wise direction for at least two complete revolutions, thus causing the plate 24 to travel toward the left until it reaches the full line position of Fig. 2, which movement of the plate 24, because of the co-operation of the stud 55 with the shoulder 54 upon the trigger 41, causes said trigger to be moved from the dotted line position (Fig. 5) to the full line position, whereupon the stud 47 will seat in the notch 46 and retain the trigger 41 in the 55 full line position until it is again released. If the key be rotated once or oftener after the plate has reached the full line position (Fig. 2), the bit 22 will strike the bottom edge 69 of the pivoted plate 58 and will 60 cause said plate to rock upon its pivot 57

until the perforation 59 in said plate is in registration with the slot 62 in the sliding plate 24 (Fig. 9); whereupon the stud 68, which projects through the slot 62, will seat in said notch 59 and keep the plate 58 elevated. If the key then be rotated in the clockwise direction, it will not actuate the sliding plate 24 because the right-hand edge (Fig. 4) of the recess 65 is beyond the path of travel of the bit 22, and it is not until the 70 plate 58 is released from the dotted line position of Fig. 9 that the key can actuate the sliding plate 24. In order that the plate 58 may thus be released, the key is moved to the full line position of Fig. 6 and given a slight turn in a counter-clock-wise direction. The bit 22 will engage one edge or wall of the slot 15, and thus tube 14 will be slightly rotated and the radial arm 16 will be swung through a few degrees of arc 85 until it rotates the left end (Fig. 1) of the spring-like member 17, to which the stud 68 is secured. As the members 17 and 9 are thus slightly separated from each other, the stud 68 is caused to move out of the notch 90 or perforation 59, whereupon the spring 60 returns the plate 58 to full line position (Fig. 9).

It will be obvious from the foregoing description of the parts and of the operation of the lock that a person must know how to use the lock. If, for example, the parts are in the dotted line position (Fig. 9), the key might rotate indefinitely without accomplishing anything, and the user must know 95 that the first step required is to produce the partial revolution of tube 14, and thus insure the release of the pivoted plate 58. Even after the sliding plate 24 and the bolts 25 carried thereupon are moved to the point 100 where the staples 4 can pass through the slots 26, the bolt 42 on the trigger 41 still prevents the staple 4 from moving, and the operator must know when and how to release the pivoted trigger 41. This lock, therefore, possesses some of the advantages of a 105 combination lock because certain knowledge upon the part of the operator is necessary to operate the device, for even though a person should be provided with a properly-fitting key, and might thus be able to move the sliding plate 24 and bolts 25 to an appropriate position, that of itself will not unlock the device, for the staples cannot be moved until the trigger 41 is released. If 110 the user should not care to carry his key with him, he can safely leave it in the lock because even though the key were there in place, an unauthorized person would not know how to use the key and could not open the lock. 115 It is obvious that the trigger 41 may be placed upon the right side (Fig. 5) of the lock instead of on the left, this being simply a reversal of parts necessitating a change in the sequence of operations; and the pos- 120 125 130

tion of the pivoted catch 48 may be shifted so that instead of being actuated on the last rotation of the key, it is to be actuated at a different time. The beveled nose 52 at one 5 end of the pivoted catch 48, must project a slight distance above the surface of the base plate of the casing 1; otherwise the edge 53 of the bit 22 would not trip the catch 48. The exact shape of the catch 48 is, of course, 10 immaterial, and numerous changes in the details and construction of parts may be made without departing from the scope of the invention.

I claim as my invention:

15 1. In a lock of the character described, the combination of a casing and a bolt-carrying sliding plate adapted to be received there- 80 within, said plate being adapted to be actuated by the key, a bolt mounted in the casing, a pivoted catch adapted to coöperate with 70 said last-mentioned bolt and hold the same against movement, means for releasing said catch thereby to permit said bolts to move in one direction, and means intermediate said bolt and said sliding plate whereby said bolt 75 is moved in the opposite direction by said plate.

20 2. In a lock of the character described, the combination of a casing, a bolt-carrying sliding plate provided with recesses, which 85 recesses are adapted successively to receive the key thereby to actuate said bolt-carrying plate, a pivoted member also carrying a bolt, and means actuated by the key for operating 90 said pivoted member.

25 3. In a lock of the character described, the combination of a casing, a bolt-carrying sliding plate provided with recesses, which 95 recesses are adapted successively to receive the key, thereby to actuate said bolt-carrying plate, a pivoted member also carrying a bolt, and means actuated by the key for operating 100 said pivoted member, said sliding plate and said pivoted bolt being actuatable independ- 105 ently of each other.

40 4. In a lock of the character described, the combination of a casing, a bolt-carrying sliding plate, a casing within which said 110 plate is received, there being openings in said sliding plate into which the means to be locked are adapted to pass, a pivoted mem- 115 ber also coöoperating with the means to be locked, means independent of said sliding plate adapted to permit the movement of said pivoted member in one direction, and means actuated by the plate adapted to cause 120 the movement of the pivoted member in the opposite direction.

45 5. In a lock of the character described, the combination of a casing, a bolt-carrying sliding plate adapted to be received there- 125 within, said plate being adapted to be actuated by the key, a bolt mounted in the casing, and means intermediate said last-mentioned bolt and said plate whereby said last-mentioned bolt is moved in one direction by said plate, and means actuated by the key adapt- 130 ed to move said last-mentioned bolt in the opposite direction.

55 6. In a lock of the character described, the

combination of a casing, a bolt-carrying sliding plate adapted to be received there- 70 within, said plate being adapted to be actuated by the key, a bolt mounted in the casing, a pivoted catch adapted to coöperate with 75 said last-mentioned bolt and hold the same against movement, means for releasing said catch thereby to permit said bolts to move in one direction, and means intermediate said bolt and said sliding plate whereby said bolt 80 is moved in the opposite direction by said plate.

7. In a lock of the character described, the combination of a casing, a bolt-carrying sliding plate adapted to be received there- 85 within, said plate being adapted to be actuated by the key, a bolt mounted in the casing, a pivoted trigger upon which said last-mentioned bolt is carried, a pivoted catch adapt- 90 ed to coöperate with said trigger and hold same against movement, means for actuating said trigger when said catch is released, means coöperating with the key and adapted to actuate said catch, thereby to release the trigger, and means intermediate said trigger 95 and said plate whereby said trigger is moved in one direction by the actuation of said plate.

8. In a lock of the character described, the combination of a casing, a bolt-carrying 95 sliding plate adapted to be received there- within, said plate being adapted to be actuated by the key, a bolt, a trigger upon which 100 said bolt is mounted, a pivot secured to the casing and upon which said trigger is adapt- 105 ed to rotate, a rocking catch adapted to rock in a plane which intersects the plane of movement of said trigger, means intermediate 110 said catch and said trigger whereby said trigger is adapted to be retained in one position by said catch, means adapted to actuate said trigger when said catch is released, said casing being recessed and one end of said 115 catch being received within said casing-recess, said end thus retained being adapted to be engaged and actuated by the key, and means intermediate said trigger and said sliding plate, said means being adapted to translate the reciprocatory movement of said sliding plate into rotation of said trigger 120 about its pivot as an axis.

9. In a lock of the character described, the combination of a casing, a bolt-carrying sliding plate adapted to be received there- 125 within, said plate being adapted to be actuated by the key, a bolt upon said sliding plate, a second bolt in juxtaposition to said first-mentioned bolt, a movable staple adapt- 130 ed to coöperate with both of said bolts, said staple being secured to the member to be locked, a spring-controlled trigger upon which said second-mentioned bolt is carried, a pivoted catch adapted to rock in a plane which intersects the plane of rotation of said trigger, said catch being provided at one end 135

with a beveled head adapted to be engaged by the key, means adjacent the other end of said catch whereby said catch is adapted to retain said trigger in a predetermined position, and means intermediate said trigger and said sliding plate adapted to translate the reciprocatory movement of said plate into movement of said trigger upon its pivot as an axis.

10 10. In a lock of the character described, the combination of a casing, a bolt-carrying sliding plate adapted to be received therewithin, said plate being adapted to be actuated by the key, a bolt upon said sliding plate, a second bolt in juxtaposition to said first-mentioned bolt, a movable staple adapted to coöperate with both of said bolts, said staple being secured to the member to be locked, a spring-controlled trigger upon which said second-mentioned bolt is carried, a pivoted catch adapted to rock in a plane which intersects the plane of rotation of said trigger, said catch being provided at one end with a beveled head adapted to be engaged by the key, means intermediate the other end of said catch whereby said catch is adapted to retain said trigger in a predetermined position, and a projection and shoulder coöoperating therewith and adapted to translate the movement of said plate into movement of said trigger upon its pivot as an axis.

11. In a lock of the character described, the combination of a casing, a bolt-carrying sliding plate provided with recesses adapted successively to receive the key, said key being adapted to enter said recesses and thereby translate the rotation of said key into longitudinal movement of said plate, a pivoted trigger, a bolt in connection with said pivoted trigger, a rocking catch, means intermediate said catch and said trigger whereby said catch is adapted to retain said trigger in one position, one end of said trigger being disposed in the path of travel of said key and being located at a point where said key will engage the same when said key has passed out of said recesses in said sliding plate.

12. In a lock of the character described, the combination of a casing, a bolt-carrying

sliding plate, a staple carried upon the member to be locked, said staple being engaged by said bolt when said plate is at the limit of its path of travel in either direction, said staple being adapted to be released from said bolt when said sliding plate is in a position intermediate the extreme limits of its path of travel, a pivoted member, a bolt in connection with said pivoted member, said second-mentioned bolt being adapted to engage the same staple that is engaged and locked by said first-mentioned bolt, a key adapted to actuate said sliding plate, and means adapted to be engaged by the key and being located intermediate said key and said pivoted plate, said last-mentioned means being adapted to be engaged by the key at a time when said first-mentioned bolt coöperates with and locks said staple.

13. In a lock of the character described, the combination of a casing, a bolt-carrying sliding plate, a staple carried upon the member to be locked, said staple being engaged by said bolt when said plate is at the limit of its path of travel in either direction, said staple being adapted to be released from said bolt when said sliding plate is in a position intermediate the extreme limits of its path of travel, a pivoted member, a bolt in connection with said pivoted member, said second-mentioned bolt being adapted to engage the same staple that is engaged and locked by said first-mentioned bolt, means intermediate said pivoted member and said sliding plate and adapted to translate the sliding movement of said plate into rotary movement of said pivoted member, a rocking catch, means intermediate one end of said catch and said pivoted member and adapted to cause said catch to lock said pivoted member in one position, the other end of said catch being placed in the path of travel of the key, and being adapted to be engaged and moved by said key, said key being adapted to actuate said plate when said key is partially rotated and being adapted to engage said catch when said key is further rotated.

In testimony whereof I have affixed my signature.

MATTHEW BURDA.
